UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE FRAME FOR AXMINSTER LOOMS.

Application filed June 22, 1923. Serial No. 647,147.

To all whom it may concern:

Be it known that I, RICHARD G. TURNER, a citizen of the United States, residing at Worcester, in the county of Worcester and State of Massachusetts, have invented a new and useful Tube Frame for Axminster Looms, of which the following is a specification.

This invention relates to tube frames used in connection with wide Axminster carpet looms and more particularly to quickly detachable means for holding the usual spool supporting brackets to the ends of the hollow bar ordinarily forming the body of wide tube frames. An object of the invention is to provide for holding the brackets to the tube frames without the use of screws, etc. by providing a bracket held rigidly to the frame by means of detachable clamping means which serves to hold the bracket to the frame by friction. By such a construction an imperfect bracket may be readily removed and a perfect one substituted therefor.

Another object of the invention is to provide means for removably securing the chain engaging spring hooks to the tube frames by extending one end of the spring into the tube and holding it tightly by the same means employed to hold the bracket in place.

With these and other objects which will appear as the description proceeds the invention resides in the combinations and arrangement of parts hereinafter described and set forth in the claims.

Referring to the drawings, wherein two forms of bracket and clamping means are shown,

Fig. 1 is a front elevation of a tube frame having the preferred form of the invention applied thereto,

Fig. 2 is an enlarged vertical longitudinal section through one end of the tube frame shown in Fig. 1,

Fig. 3 is a vertical section on line 3—3 of Fig. 2,

Fig. 4 represents a front and side elevation of the preferred form of clamp,

Fig. 5 is a view similar to Fig. 2 but showing a modified form of the invention,

Fig. 6 is a section on line 6—6 of Fig. 5, and

Fig. 7 is a front elevation of the modified form of clamp shown in Fig. 5.

Referring to Figs. 1-4 of the drawings, the tube frame is shown as formed of a hollow metallic bar 10 to which are secured the ordinary yarn tubes 11 which receive yarn from spools 12. Axminster looms of the type which employ tube frames are provided with two continuous chains, (not shown on the drawings) one at each side of the loom, to which the frames are detachably held by means of brackets 13 and springs 14. The spools 12 are mounted in end bearings 15 carried by the brackets.

In carrying out the preferred form of my invention, I form each bracket with arms 20 and 21, both of which extend into the hollow bar 10. Arm 21 is in this instance formed with the bearing member 15, the latter being welded, riveted or otherwise secured to the bracket while arm 20 is formed integral with the bracket 13. The bracket is provided with a slot 22 through which extends the bent end 23 of the spring 14, said bent end projecting into the hollow bar and lying parallel to arm 20. A boss 24 pressed up from the bracket 13 passes through a hole punched in the spring 14 and positions the latter for proper engagement with operating parts of the loom (not shown).

Bracket 13 is held to the bar 10 by means of a clamping block 25 substantially of the form shown in Figs. 2 and 4, where said block is shown as having a length greater than its width. The ends of the block are roughened as at 25^a to prevent the block from jarring loose from the position shown in Fig. 2. A non-circular aperture 26 is formed in the block and affords a means for rotating the block on its own axis. In order to prevent the accidental displacement of the block during assembly of the parts, arm 20 is bent toward arm 21 as at 27, the distance between the ends of the arms being less than the least dimension of the block 25.

When applying the bracket to the tubular bar, the bracket, spring hook and block are assembled as shown in Fig. 2, except that block 25 has its long axis disposed at some angle other than a right angle with respect to arms 20 and 21. The latter are then inserted in the bar 10 and the bracket moved

to position, the block 25 being retained by the upwardly curved end 27 of arm 20. An appropriate tool is then inserted through hole 28 formed in the bar 10 into opening 26 and the block turned until it assumes the position shown in Fig. 2, with the long axis substantially at right angles to the arms of the bracket.

The turning of the block forces the arms 10 tightly against the adjacent parts of the bar 10, since the parts are so proportioned that the longer axis of the block plus the thickness of arms 20 and 21, together with end 23 of the spring is slightly greater than the 15 distance between the top and bottom walls of bar 10. The end 23 of the spring 14 is located between the clamp and arm 20 and is thus held in place.

The modified form shown in Figs. 5, 6 and 20 7 employs a somewhat different form of 20 clamping block and the arms from the bracket are located one inside and the other outside the tube.

Bracket 30 carries arms 31 and 32, the 25 former similar to arm 20 except for an additional boss 33 to pass through bent end 34 of spring 35 and the latter arm having struck therefrom ears 36 to enter corresponding openings 37 formed in tube 38.

The modified block 39 has curved surfaces 40 which are continuous with parallel plane faces 41 each of which extends on opposite sides of a line passing through the center of the clamp and normal to faces 41. 35 The distance between faces 41 is less than the distance between corners 42 or the points where faces 41 connect with the curved faces 40.

The modified form is assembled in a manner similar to the preferred form, the block being placed on one of its long sides between the arm 31 and end 34 of the spring 35. Arm 31 is then inserted in the tube and the bracket lowered so that ears 36 fit into their 45 respective openings in the tubular bar 38. By means of a suitable tool inserted in non-circular aperture 43 in block 39 the latter is turned clockwise (as viewed in Fig. 5) until the faces 41 lie flat against adjacent parts.

The parts are so proportioned that when in the position shown in Fig. 5 block 39 will force the arms 31 and 32 against the bar and hold the same in position by friction. Because of the relation of faces 40 and 41, and corners 42, the block is locked and accidental removal of the bracket due to loosening of the block is prevented.

From the foregoing description it is apparent that I have provided a very simple means for holding spool bearing brackets to tube frames, the fastening and unfastening of the parts being readily accomplished by the partial rotation of a clamping block 60 which is located in the tube frame where it

will not be engaged by the parts of the loom which operate on the tube frame. Also, the spring hook is held in place by the clamping block without the use of screws, etc. 70

Having thus described my invention it will be evident that changes and modifications can be made therein by those skilled in the art without departing from the spirit and scope thereof as set forth in the claims, 75 and I do not wish to be otherwise limited to the details set forth herein, but what I claim is:

1. In a tube frame for Axminster looms, a hollow tubular member, a spool supporting bracket, an arm rigid therewith extending along a portion of the tubular member, and clamping means to frictionally hold the arm to the member, said means including an element housed in said tubular member and 80 rotatable on its own axis either to clamp said member and arm together or to release said arm from the tubular member. 85

2. In a tube frame for Axminster looms, a tubular member, a spool supporting bracket 90 having an arm extending into the member, and a clamping block located within the member and interposed between said arm and a portion of the tubular member, said block being movable angularly with respect 95 to the arm and member and serving when turned to force the arm against the tubular member.

3. In a tube frame for Axminster looms, a hollow tubular member, a spool supporting 100 bracket having an arm extending into said member, and a clamping block located within the member arranged to be tight and loose with respect to the arm and member, said block being formed with a non-circular portion accessible through an opening in the tubular member by means of which the block may be turned to be either tight or loose with respect to said arm and member. 105

4. In a tube frame for Axminster looms, a hollow tubular member, a spool supporting bracket having a pair of arms extending therefrom and into the tubular member, and a clamping block located in the tubular member and between the arms and being movable angularly with respect to the arms 110 to force said arms against the tubular member and hold the arms and tubular member together by friction. 115

5. In a tube frame for Axminster looms, a hollow tubular member, a spool supporting bracket having arms extending therefrom and into the member, and a clamping block located between said arms and being rotatable on its own axis to spread said arms apart 120 and force them against the member to which said arms are held by friction. 125

6. In a tube frame for Axminster looms, a hollow tubular member, a spool supporting bracket, a spring hook, said bracket and 130

- hook having portions extending into the tubular member, and means located within the member and having a portion thereof, accessible through an opening in the member 5 for frictionally holding said bracket and hook to said tubular member.
7. In a tube frame for Axminster looms, a tubular member, a bracket having a positioning boss thereon, a spring having an opening therein to receive said boss, the end 10 of the spring projecting into the tubular member, and means within said member to hold said end of the spring.
8. In a tube frame for Axminster looms, a 15 tubular member, a spool supporting bracket having an arm extending therefrom into the member, a clamping block located in the member and arranged to be tight or loose with respect to said arm, and means to retain the block when loose with respect to 20 said arm, said means being independent of the block when the latter is tight with respect to said arm.
9. In a tube frame for Axminster looms, a 25 hollow tubular member, a spool supporting bracket having a pair of arms thereon and extending into said member, and a clamping block located between the arms and forcing
- the arms against the member, the distance between the ends of the arms being less than 30 the least dimension of the block.
10. A holding block for hollow Axminster tube frames having brackets with arms extending along portions of the frame and having an opening therein, said block being 35 of greater dimension in one direction than in the other, and having a portion accessible through the opening in the frame by which said block may be rotated to cause the greater dimension thereof to lie substantially 40 perpendicular to said arms of the bracket to force said arms against adjacent portions of the frame.
11. In a tube frame for Axminster looms, a tubular member, a bracket having arms 45 thereon extending along portions of the member, and a block rotatable on its own axis in engagement with at least one of said arms to hold the same against said member by friction, said block being of greater 50 length than breadth and having spaced points on each end thereof to engage parts adjacent thereto.

In testimony whereof I have hereunto affixed my signature.

RICHARD GREENLEAF TURNER.
